UNITED STATES PATENT OFFICE

AVILA O. THOMAS, OF DETROIT, MICHIGAN, ASSIGNOR TO THE STRUCTURAL CONCRETE UNITS CORPORATION, OF DETROIT, MICHIGAN, A CORPORATION OF DELAWARE

UNIT WALL CONSTRUCTION

Application filed September 16, 1929. Serial No. 392,945.

This invention relates to wall constructions, and particularly to interfitting wall-forming units, precast of concrete or other cementitious material.

5 An object of the invention is to so interlock and tie together a system of precast building units as to form a rigid, substantial wall such as may be quickly and easily erected, at relatively low cost.

10 Another object is to form a hollow wall of spaced vertical sectional columns and inner and outer wall plates extending between and abutting said columns, and to extend tie members through the columns to connect 15 said plates.

A further object is to form said columns of complementary channel-shaped units, and to utilize said tie members to hold said units securely in complementary relation.

20 A still further object is to provide means for quickly inter-connecting a pair of column-forming units in complementary relation, preliminary to their assembly in a wall. These and various other objects the invention attains by the construction herein-after described and illustrated in the accompanying drawings, wherein:

Fig. 1 is a plan view of a portion of a wall embodying the invention.

30 Fig. 2 is an elevational view thereof.

Fig. 3 is an enlargement of a portion of Fig. 1.

Fig. 4 is a fragmentary, perspective view of a top portion of one of the column-forming units.

Fig. 5 is a similar view of the complementary portion of one of the wall plates.

Fig. 6 is a vertical cross sectional view of the abutting ends of one of two of the column units, one superposed on the other, taken upon the line 6—6 of Fig. 3.

Fig. 7 is a vertical section taken upon the line 7—7 of Fig. 3 disclosing a connection between two wall plates resting one 45 upon another and showing the engagement of a tie member with one of said plates.

In these views, the reference characters 1 and 2 designate a pair of channel-shaped column-forming units of concrete or the like, 50 which, preliminary to their positioning in a

wall, are oppositely arranged in the abutting relation, clearly appearing in Figs. 1 and 3. Said units are of a height suited for convenient handling, and a sufficient number thereof may be set one upon another to build 55 up a column of desired height. Preferably the abutting faces of said units are formed with interfitting V shaped ribs and channels 3 extending the full height of said units to aid in their quick and accurate assembly. 60

Cast into each unit 1 and 2 is a pair of metal rods 4, extending from top to bottom thereof, substantially at the junctures of their relatively transverse portions, acting to reinforce the units and also providing for 65 rigidly connecting superposed units. Thus said rods terminally project into recesses 5 formed in the end faces of the units and are engageable within said recesses by coupling sleeves 6 transversing the horizontal 70 meeting plane of the units.

A tie connection is established between each pair of units 1 and 2 at their ends, by a pair of metal rods (or heavy wires) 7, extending in the recesses 5 and having their 75 ends looped, as indicated at 8, to embrace the rods 4. When initially set in said recesses, the loops 8 are open, as appears in dash lines in Fig. 3, said loops being subsequently closed by pliers or some other suitable tool 80 to tightly hug the rods 4.

The columns formed by the units 1, 2 are suitably spaced, and between the same are extended pairs of spaced wall plates 10, precast of concrete or the like, a suitable number thereof being superposed one on another to achieve the desired height. Said plates may be set flush with the columns, and their extremities are preferably formed with positioning ribs 11 coextensive in height with 85 said plates and offset from the outer faces of the latter to fit into channels 12 exteriorly formed in the units 1 and 2. It is preferred to reinforce the plates 10 by centrally imbedding therein sheets 13 of a wire mesh or other foraminated metallic fabric, substantially coextensive with said plates. 90

The ends of the wall plates are tied to the columns by pairs of diagonally crossed metal tie bars 14, arranged between the su- 100

perposed column sections. Each unit 1 and 2 is notched outwardly from its recesses 5, as indicated at 15, to accommodate said bars, and the top and bottom edges of the wall 5 plates are recessed as indicated at 16 and 16', adjacent to the columns for a like purpose. A pair of anchorage pins 17 are cast into the top portion of each wall plate, one at each end thereof, and project vertically into the recesses 16, and a similar pair of anchorage pins 17a axially aligned with the pins 17 are imbedded in the bottom portion of each plate 10, and project into the recesses 16'. A coupling sleeve 18 within the communicating recesses 16 engages the aligned ends of said pins as best appears in Fig. 7, thereby assuring accurate vertical registration of the tiers of wall plates. The bars 14 retain the plates 10 at opposite sides of the columns 10 properly engaged with the latter, and furthermore act through said plates to supplement the tie rods 7 in maintaining the proper abutting relation between the column units 1 and 2.

25 After the columns have been built up to the desired height, they may be filled with concrete as appears in Fig. 1 to further increase their rigidity.

30 The described construction is simple and easily erected, and its parts are adapted for rapid machine production. The tie members are also simple and inexpensive, and may be rapidly applied as each successive tier of the wall is completed.

35 The construction is furthermore one that imparts a high degree of rigidity to the completed wall, permitting the latter to be safely carried to a considerable height and giving it substantially all of the advantages 40 of a monolithic hollow wall, while far less expensive.

45 The invention as exemplified in the drawings discloses the columns as equal in width to the wall. It is, however, to be understood that it frequently may be desirable to employ columns of greater width than the intervening portions of the wall, particularly when the columns are required to carry heavy loads. Without divergence from the 50 principles illustrated by the drawings, differently proportioned columns may be employed without variation in proportions of the illustrated wall plates or in the spaced relation of the paired plates. Formation of 55 the column-forming units separately from the wall plates renders the several units lighter and more readily handled than would be the case if the wall plates and column units were integrated, as well as permitting the aforementioned variation in the 60 column width relative to the width of the wall proper.

65 While it is apparent that the illustrated embodiment of my invention herein disclosed is well calculated to adequately fulfill

the objects and advantages primarily stated, it is to be understood that the invention is susceptible to variation, modification and change within the spirit and scope of the subjoined claims.

What I claim is:

1. In a wall construction, a plurality of hollow columns, each comprising one or more pairs of vertically abutting units, wall plates between said columns and abutting said units, and a common means for maintaining the abutting relation of the column-forming units with each other and with said wall plates.

2. A wall construction comprising a pair of vertically abutting, column-forming units, a pair of wall plates oppositely abutting the column formed by said units, and a tie member extending through said column and connecting said units.

3. A wall construction comprising a pair of column-forming units, abutting in a plane parallel to the wall, a pair of wall plates abutting the respective units at opposite sides of the column, and a tie member extending diagonally through the column maintaining engagement of said plates with the column, and of said units with each other.

4. A wall construction comprising a pair of vertically abutting, column-forming units, a pair of wall plates extending substantially parallel to the abutment plane of said units and abutting said units at opposite sides of the column formed thereby, and tie connections through the column between said wall plates.

5. A wall construction comprising a pair of vertically abutting, column-forming units, pairs of spaced wall plates abutting opposite sides of said units parallel to their plane of abutment, and diagonal tie members extending through the column and connecting said units.

6. A wall construction comprising a pair of vertically abutting, column-forming units, wall plates abutting opposite sides of the column formed by said units in a diagonally opposed relation, and interlocked with said column, and a tie member extending through the column and connecting said plates.

7. A wall construction comprising a pair of vertically abutting, column-forming units, a pair of spaced wall plates abutting each side of the column formed by said units and interlocked with said column, and pairs of diagonal tie members extending through the column and connecting said wall plates.

8. A wall construction comprising a column, wall plates abutting opposite sides of said column, and connections between said plates passing through the column.

9. A wall construction comprising a col-

umn, a pair of spaced wall plates abutting each of two opposite sides of said column, and tie members diagonally extending through the column and connecting said 5 wall plates.

10. A wall construction comprising a column, a pair of spaced wall plates abutting each of two opposite sides of said column and having a tongue and groove engagement 10 with said column, and tie members diagonally extending through the column and maintaining such engagement.

11. A wall construction comprising a pair of vertically abutting column-forming units, 15 spaced pairs of wall plates abutting each of two opposite faces of the column formed by said units, and engaging shoulders on said units to maintain the spaced relation of said plates, and tie members diagonally 20 extending through said column, connecting said plates and holding same against said shoulders of the column.

12. A wall construction comprising a pair of vertically abutting column-forming units, 25 spaced pairs of wall plates abutting each of two opposite faces of the column formed by said units, and terminally fitting into vertical grooves in said units, and a common means for maintaining the abutting relation 30 of the column-forming units and for holding said wall plates in engagement with said grooves.

13. A wall construction comprising super- 35 posed units having communicating recesses in their abutting faces, aligned anchorage pins imbedded in said units and projecting into said recesses, and a sleeve within said recesses surrounding the adjoining ends of said pins to maintain vertical alignment of 40 said units.

14. A wall construction comprising super- 45 posed units having communicating recesses in their abutting faces, members imbedded in said units having ends adjoining within said recesses, and means detachably connecting said ends within said recesses to resist relative lateral movement of said units.

15. A wall construction comprising super- 50 posed cementitious units, metal rods imbedded in said units extending from top to bottom thereof, and having adjoining ends projecting from the units, and a sleeve surrounding said adjoining ends and resisting relative lateral movement of said units.

55. 16. A wall construction comprising units arranged in superposed courses, tie mem- bers connecting the units of each course, and anchorage elements for said tie members im- bedded in said units, said anchorage ele- 60 ments of superposed units being interen- gaged to resist relative lateral movement of the superposed units.

17. A wall construction comprising a pair 65 of abutting units respectively forming inner and outer faces of a wall, pairs of anchor-

age pins imbedded in said units in opposed relation, and projecting substantially verti- cally from the units, and metal tie members having looped extremities engaging the pro- jecting ends of the paired anchorage pins. 70

In testimony whereof I sign this speci- fication.

AVILA O. THOMAS.
